(57) **CLAIM**

The ornamental design for a container handle, as shown and described.

DESCRIPTION

FIG. 1 is a perspective view of a container handle according to one embodiment of the present invention.

FIG. 2 is a front view of the container handle of FIG. 1.

FIG. 3 is a rear view of the container handle of FIG. 1.

FIG. 4 is a right-side view of the container handle of FIG. 1.

FIG. 5 is a left-side view of the container handle of FIG. 1; and,

FIG. 6 is a top view of the container handle of FIG. 1.

The broken lines are for illustrative purposes only and form no part of the claimed design.

1 Claim, 6 Drawing Sheets
